US0D1090790S

(12) **United States Design Patent** (10) **Patent No.:** **US D1,090,790 S**
(45) **Date of Patent:** **** Aug. 26, 2025**

(54) **APERTURE COVER**

(71) Applicant: **VACUUM TECHNOLOGIES, LLC**,
Sheridan, WY (US)

(72) Inventors: **Justin Taylor Heaps**, Ranchester, WY
(US); **John F. Tucker**, Sheridan, WY
(US); **Jared Leroy Meacham**,
Sheridan, WY (US)

(73) Assignee: **Vacuum Technologies, LLC**, Sheridan,
WY (US)

(**) Term: **15 Years**

(21) Appl. No.: **29/943,191**

(22) Filed: **May 20, 2024**

Related U.S. Application Data

(62) Division of application No. 29/779,674, filed on Apr.
20, 2021, now Pat. No. Des. 1,032,978.

(57) **CLAIM**

The ornamental design for an aperture cover as shown and
described.

DESCRIPTION

FIG. 1 is a perspective view of an aperture cover according
to an embodiment showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and

FIG. 8 is a perspective view of the design in a use environment
engaged over the aperture of a vacuum separator;

FIG. 9 is a perspective view of an aperture cover according
to a second embodiment of our new design;

FIG. 10 is a front elevation view thereof;

FIG. 11 is a rear elevation view thereof;

FIG. 12 is a top plan view thereof;

FIG. 13 is a bottom plan view thereof;

FIG. 14 is a left side elevation view thereof;

FIG. 15 is a right side elevation view thereof; and,

FIG. 16 is perspective view of the design shown in FIG. 9
in its use environment engaged over the aperture of a
vacuum separator.

The broken lines in the figure drawings represents
unclaimed environment only and form no part of the claimed
design.

1 Claim, 12 Drawing Sheets
